S. S. PORTER

END POST

Filed June 9, 1923

FIG. 1.

Inventor
Sidney S. Porter
By Aug. 22, 1923, M.T.G.

UNITED STATES PATENT OFFICE.

SIDNEY S. PORTER, OF EVANSTON, ILLINOIS, ASSIGNOR TO CALUMET STEEL COMPANY, OF CHICAGO, ILLINOIS, A CORPORATION OF ILLINOIS.

END POST.

Application filed June 9, 1923. Serial No. 644,297.

To all whom it may concern:

Be it known that I, SIDNEY S. PORTER, a citizen of the United States, residing at Evanston, in the county of Cook and State 5 of Illinois, have invented new and useful Improvements in End Posts, of which the following is a specification.

This invention relates to metal posts, and more particularly to end posts for grape 10 arbors having horizontal wires, like a fence, for supporting the same.

One object of my invention is to provide the end posts with anchor means made and arranged to resist the pull of the wires 15 thereon, due to the tautness of the wires and the weight of the vines thereon.

Another object of my invention is to provide either one or both end posts with wire winding devices, one for each wire, and 20 made a part of the post structure, so that separate devices for this purpose are avoided and tightening of the wires permitted from time to time by actuating the winding devices to take up any slack in the wires.

25 A further object of the invention is to provide an improved form of lock for releasably holding the winding devices against rotation so that the wires may be kept taut after being tightened.

30 The invention consists further in the matters hereinafter described and more particularly set forth in the appended claims.

In the accompanying drawings—

Fig. 1 is a view of a grape arbor employing 35 an end post of my invention;

Fig. 2 is an enlarged side view of said post;

Fig. 3 is a front view of the same;

Fig. 4 is a top plan view of the same; 40 and

Figs. 5 and 6 are perspective views of details to be hereinafter described.

The arbor shown in Fig. 1 comprises two end posts 1, 2, intermediate line posts 3, 3 45 and horizontal wires 4, 4 stretched between and secured to said posts for supporting the grape vines 5, 5. The wires 4, 4 in the particular installation shown, are two in number and are vertically spaced apart, being secured to the upright line posts 3, 3 in any suitable manner, as by staples 6, 6. Said line posts 3 are of metal, preferably rolled in the form of T-bars, with holes therein for the staples to pass through and be

clinched against the back of the front flanges 55 of said posts.

The end posts 1, 2 are also made of metal, preferably rolled, and each is provided on the portion embedded in the ground with two substantially flat anchor plates 7, 7. 60 Said plates 7, 7 are secured to the posts 1, 2 in any suitable manner, as by bolts 8, 8 and are arranged to extend across and project beyond both sides of the same, as shown. These plates 7, 7 are spaced apart length-

wise of the post so that one plate will be adjacent the lower end of the post and another higher up adjacent the surface of the ground, as indicated in Fig. 1. By this arrangement the anchor plates 7, 7 engage the 70

earth, in which they are embedded, at separate points, and resist the constant tendency of the weight of the grape vines on the wires 4, 4 to sag them and pull the end posts 1, 2 toward each other. These posts 1, 2 are initially set in the ground at an inclination 75

backward, as shown in Fig. 1, to resist this pull. To further resist this pull, the posts 1, 2 are made U-shape in cross section and are set up in the ground with their channels 80

facing so that the same below the ground surface are filled with earth.

To take up the slack in the wires 4, 4, from time to time, without resetting the end posts at further angles backward, as heretofore required, I provide on one end post, namely, the one 1, wire tighteners or take up devices. Each device comprises a wind-

ing member or drum 9, rotatably supported by the side walls 10, 10 of post 1 and extending between them, as shown in Fig. 4. Said member 9 has its ends projecting through and beyond said walls 10, 10 and at one end, outside said post, there is a trans-

verse hole 11 to receive a turning rod or handle 12. Between its ends, said member 9 has a hole 13 to receive an end of the adjacent wire 4 and enable it to be wound thereon, as the member 9 is turned.

To hold the member 9 from turning to release the tautness of a wire wound thereon, I provide a lock 14. This is made in one piece and of the shape shown in Fig. 6. As there illustrated, said lock is bent to provide a mid-section 15 and parallel end 105 sections 16, 16. The latter are on the same side of the mid-section 15 and make the lock 14 somewhat U-shape in form.

The mid-section 15 extends through a hole 17 at the end of the member 9 opposite the handle 12 and permits turning the lock 12 from a position standing outside of the post, 5 as shown in Fig. 3 to a position spanning the post as shown in Fig. 4. In the latter position, the lock 14 has its ends 16, 16 engaging the back and one front edge of the post 1 and holds the member 9 against turning 10 to hold the wire from slackening. The lock 14 spanning the post 1 in this manner makes the lock effective at each half turn of the member 9.

The other end post 2, may, if desired, be 15 provided with these wire take up devices, although not needed when the same are carried by and form a part of the other post 1. When not so provided, the wires 4, 4 20 may be attached or secured to the post 2 in any suitable manner sufficient to stand the strain when made taut by turning the members 9, 9.

By making the post 1 U-shape, side walls 10, 10 are provided as supports for the members 9, 9, and thus make possible the incorporation of the wire tightening devices directly in the post structure and be a part of it. This avoids the use of separate wire 25 tighteners or the fastening of wire tightening devices on the post. Moreover, it allows for tightening the wires 4, 4 from time to time without resetting the posts, and further, avoids the uses of braces or guyes to 30 interfere or hinder plowing between the vines 5, 5.

While I have shown and described in detail herein, anchor plates and a post with wire tighteners made in accordance with my invention, it is, of course, to be understood 40 that the details of construction and arrangement of parts may be variously modified without departing from the spirit and scope of my invention.

I claim as my invention:

45 1. A post, comprising a body section, U-shape in form, a wire winding member extending across the channel of said post and rotatably supported by the side walls thereof, said member extending beyond the side

walls of said post and provided at one end 50 outside said post with an opening to receive means for turning said member, and a lock carried by the other end of said member outside said post to be swung into and out of spanning engagement with said post 55 for releasably holding said member against rotation.

2. A post, comprising a body section substantially U-shape in form and having aligned holes in its side walls, a wire winding member extending across the channel of said post between said side walls and having its ends rotatably supported in said holes with the ends of said member projecting beyond said side walls, one end of said 60 member being formed to receive means for turning said member, and a lock at the other end of said member, said lock having a mid-section engaged with said member and end sections transverse to said mid-section 70 and turnable therewith into and out of spanning engagement with the back and one of the front edges of the post for releasably holding said member against rotation.

3. A post, comprising a body section substantially U-shape in form and having aligned holes in its side walls, a wire winding member extending across the channel of said post between said side walls and having its ends rotatably supported in said 75 holes with the ends of said member projecting beyond said side walls, one end of said member being formed to receive means for turning said member, and a lock at the other end of said member outside said post, said 80 lock having a mid-section engaged with said member and end sections transverse to said mid-section and turnable therewith into and out of spanning engagement with the back and one front edge of the post for releasably 85 locking said member against rotation, said lock being carried by said member in a manner to span the post at each half turn of said member.

In testimony that I claim the foregoing 90 as my invention, I affix my signature, this 7th day of June, 1923.

SIDNEY S. PORTER.
